DESIGN FOR A LIPSTICK HOLDER

Sidney Isabelle Sohmer, Miami Beach, Fla.

Application November 26, 1946, Serial No. 135,105

Term of patent 7 years

(Cl. D86—10)

To all whom it may concern:

Be it known that I, Sidney Isabelle Sohmer, a citizen of the United States, residing in Miami Beach, county of Dade, State of Florida, have invented a new, original, and ornamental Design for a Lipstick Holder, of which the following is a specification, reference being had to the accompanying drawing, forming a part thereof, in which:

Fig. 1 is a side elevational view of my new design of lipstick holder, showing the two elements thereof in separated position;

Fig. 2 is a side elevational view of my new design with the two elements thereof in closed position,

Fig. 3 is a top plan view thereof, and

Fig. 4 is an end view of the upper half of said holder looking toward the top of the drawing.

I claim:

The ornamental design for a lipstick holder, as shown.

SIDNEY ISABELLE SOHMER.
